UNITED STATES PATENT OFFICE.

ROBERT W. SCOTT, OF BOSTON, MASSACHUSETTS, ASSIGNOR, BY MESNE ASSIGNMENTS,
TO SCOTT & WILLIAMS, INCORPORATED, A CORPORATION OF MASSACHUSETTS.

TUCK-STITCH MECHANISM FOR KNITTING-MACHINES.

1,311,623.

Specification of Letters Patent. Patented July 29, 1919.

Application filed July 25, 1914. Serial No. 853,053.

To all whom it may concern:

Be it known that I, ROBERT W. SCOTT, a citizen of the United States, and resident of Boston, in the county of Suffolk and State of Massachusetts, have invented certain new and useful Improvements in Tuck-Stitch Mechanism for Knitting-Machines, of which the following is a specification.

My invention relates to devices for the formation of tuck stitches at predetermined wales of knit fabrics such as stockings.

I have illustrated one embodiment of my invention in connection with a circular hosiery knitting machine not herein claimed, but it will be understood that my device is applicable without substantial change to other knitting machines.

In the accompanying drawings:

Figure 1 is a rear elevation showing so much as is necessary of such a machine having my improvement applied thereto;

Fig. 2 is a right side elevation;

Fig. 3 is a plan view taken above the bed plate;

Fig. 4 is an internal development of the cam cylinder;

Fig. 5 is a diagram illustrating one product of the machine;

Fig. 6 is an illustration of the normal and special needles.

It is desirable in many types of hosiery to form longitudinal markings, which may occur so frequently as to constitute a longitudinally striped pattern, or be restricted to parts only of the stocking, to mark off surfaces or parts of the articles for the improvement of its appearance or its structure. While my machine is applicable to these and other uses, I shall describe one illustrative form of it for knitting a stocking, Fig. 5 having a high-spliced area H at the back of the ankle and a spliced sole, with a line of stitching T produced by my new devices marking the borders of the high splicing and the sole, as illustrated in Fig. 5.

Referring now to Fig. 2, in machines of the type illustrated, the driving and control mechanism include a power shaft 30 through which the machine is driven and a pattern or cam shaft 80 carrying pattern surfaces to determine the orderly operation of the parts, the driving devices also including a rotary-reciprocatory mechanism comprising a shaft 76, a link 70 and a crank pin 62

fast upon a shaft 55 actuated from the drive shaft 30 through a gear 65, at a rate less than the rate of the shaft 30. During the normal round-and-round operation of the machine, for knitting the leg and foot of a stocking for instance, the knitting head may be driven through pulley 47, a gear not shown attached to said pulley, the gear 65, the gear 60, a pinion on the shaft 30, and the bevel gear 31, or directly through shaft 30, and pulley 42.

The gear 65 rotates at a speed constantly related to that of the knitting head, which in the machine illustrated comprises a rotating needle cylinder. In the instance shown the ratio is one revolution of the gear 65 to four rotations of the knitting head.

For making a mark at each side of the stocking, I prefer to so move one or more special needles at each side of the circle as to tuck or accumulate loops upon them during the knitting of one or more courses on the remaining needles, then to knit at a succeeding course or courses, and so on. The needles engaged in this operation must be capable of normal operation during the knitting of the remainder of the article.

The elevation of the normal needles by the upper surfaces of the cams 6 and 7 or by the jacks 380 is sufficient to clear a previous loop at the knocking-over level past the end of the latch. I tuck upon a predetermined special needle or needles n^3 having a latch n^4 longer than the normal needles, as illustrated in Fig. 6. The advance of such a needle by the normal advancing surfaces of cams 6 and 7 is insufficient to clear its latch. A needle n^3 , so long as it travels in the same path as the remaining needles, will accumulate in its hook one yarn at each passage past the yarn feeding point at the mean location of the knitting wave formed by cams 6 and 7.

In order to cause the special needle n^3 to clear its loops to knit normally at the next revolution before accumulating other loops, I provide a supplemental cam 416 following the following stitch cam 6, in the direction of travel of the needles for rotary work shown by the arrow N, Fig. 4.

My said machine may be provided with a splicing mechanism controlled from said shaft 80, for instance by cams 501 on the drum 120 geared to said shaft, coacting

through a thrust-bar 460^b with a yarn guide actuated to feed yarn to a segment only of said needles.

For a usual type of stocking the splicing 5 yarn is fed to the short butt needles n^1 employed for knitting the heel and toe pockets, and in this case the special needles n^3 may form a part of the high butt series, being placed at, or one or two needles inside of, 10 the ends of the series of long butt needles n^2 as indicated in Fig. 4.

With the particular arrangement above suggested in which the special needles are long butt needles, cam 416 when adjusted 15 is positioned outward from the axis of the machine to encounter and move the long butts only.

The height of the highest part of the cam 20 416 above the ledge 4 is such as to cause a needle approaching it in the direction for rotary work to be elevated to the level shown in Fig. 4, which level is high enough to clear the long latch needles n^3 , but not high enough to cause needles elevated by 25 the cam 416 to encounter the widening picker 680.

During the normal operation of a hosiery knitting machine of the type indicated the switch cam 415 is in an elevated inward 30 position, where it will encounter and take down nearly to the level of the ledge 4 needles approaching it at any level, whatever the length of their butts.

It will be seen that if the cam 416 is positioned as indicated, cam 415 remaining in 35 its normal position, that the rotation of the machine will cause all of the long butt needles to pass above the cam 416, said needles being restored to the level of the ledge 4 at 40 the cam 415 at each revolution.

The cam 416 may be made as a swinging switch cam generally similar to the switch cam 415 employed to elevate the long butt needles prior to reciprocal knitting for heels 45 and toes. As shown, said cam is carried by a mounting movable toward and away from the needles, being formed integrally with a short axis 417 held for rotation by a spring 418 in a bore 419 in a lever 420, which rotation is limited by a pin 421, so that the 50 cam is normally positioned with its point slightly below and outside of the ledge 4 of the cam ring.

I provide means for positioning the cam 55 416 as described during normal rotary knitting, and for withdrawing the said cam at intervals of two or more revolutions during one or more passages of the long butt needles, then again reinserting said cam during 60 the passage of the short butt needles in time with revolutions of the needle cylinder, so as to clear the special needles n^3 in the desired manner.

Preferred mechanism for this purpose 65 comprises said lever 420 pivoted at the back

of the machine on the standard E, by means of separated lugs 422 perforated for said standard which lugs straddle the boss c holding said standard, vertical adjustment being provided for by collars d and e, of 70 which the latter may be a part of a yarn supply bracket. A screw f in said lever 420 playing on the upper flat surface of the bed plate D serves as a support to prevent yielding of said lever downwardly.

75

Said lever 420 extends freely around the back of the machine to the left side thereof at the desired location for the cam 416 and is provided with a depending portion 423 bored for a plunger 424 adjustable by a 80 screw and jam nut 425. A spring 426 tends to rock lever 420 on standard E to withdraw cam 416 to an outer idle position.

The plunger 424 lies in the plane of the cams 65^a and 65^b removably attached by 85 screws to the face of the gear 65, which cams may be substantially 180° apart, so that the plunger 424 will be encountered by said cams and moved outwardly twice during each four revolutions of the knitting 90 head.

Movement of the lever due to the said cams 65^a, 65^b and the rotative position of said cams or gear 65 is such as to take the cam 416 from a radially withdrawn idle 95 position at the time of passage by it of the short butt needles to an inward adjusted position determined by the plunger 424 and screw 425 and to hold said cam 416 in this position during one passage of each of the 100 special needles n^3 . When only one cam 65^a is attached, this will occur at every fourth revolution, and with both cams as shown at every second revolution. By the described arrangement the cam 416 is out of contact 105 with the short butt needles employed for knitting the heel and toe, but it will be obvious that said cam is capable of yielding upon the reciprocatory stroke opposite in direction to the arrow N, and that, in case 110 some of the long butt needles approach it at the level of the ledge 4 in the opposite direction, their position will not be disturbed. While I have shown the cams 65^a 65^b as attachments of the gear 65, it will be 115 obvious that they may be placed upon any part of a machine to be equipped with my new devices moving in a constant relation with the motions of the knitting head.

In order to predetermine the beginning 120 and end of the tucking operation in time with the remaining instruments of the machine, I provide means for holding the lever 420 away from contact with its actuating cams 65^a and 65^b. Preferred means for this 125 purpose comprise a bell crank lever 110 pivoted on a screw stud 76^a in one end of the shaft 76, the horizontal arm of said lever resting above and in the plane of cams 112 on the periphery of a speed-changing drum 130.

102 attached to the right hand end of the pattern shaft 80 in my said machine. Adjusting screw 113 carrying a jam-nut in the depending arm 423 of said lever 420 takes 5 against the upright portion of the lever 110 to hold said lever 420 and the cam 416 in the position for operation of said cam. The absence of a cam 112 on the drum 102 will thus determine the withdrawal of the 10 cam 416 by the action of the gear 65 and its attached cams. The drum 102 makes one revolution during each article, and the placing in the fabric of tuck stitches is accurately determined by the position of cams 15 112, which are adjustably screwed on the face of the said drum 102.

In the machine improved when the machine is intended to be used for knitting upon transferred fabric sections provision is 20 made for automatically withdrawing the stitch cams 6 and 7 to level the needles at the end of the operation of knitting the previous article.

Devices for this purpose, as described and 25 claimed in my application Serial No. 807,535, filed December 18, 1913, [Letters Patent No. 1,150,547, dated August 17, 1915] comprise a cam on one of the thrust bars, such as 460 reacting with a pin 374 in 30 a yoke 373 forming a part of the segment 370 carrying said stitch cams. This withdrawal, by the timing of the machine, always occurs with respect to the rotation of the knitting head at a predetermined one 35 of alternate courses which, when the cam 416 is being actuated is that course at which said cam is withdrawn to leave the special needles at the tuck position.

In order now to prevent interference by 40 the tucking cam with the leveled needles at this point in the operation, I provide a gap between cams 112 on the drum 102 near the place at which the lug 106 operates the belt shipper to stop the machine, to permit plunger 424 to enter between the cam 65^a and 65^b at the revolution upon which the stitch cam is withdrawn, after which revolution the machine stops.

The cam 416 is thus removed from the 50 possibility of contact with the long butt needles during movement of the machine prior to stoppage or before beginning a new article, to level the needles.

The shaft 80 and the drum 120 rotate 55 in unison, whereby the position in the fabric of the spliced areas H and S controlled by cams 501 and the tucked mark T are related in the desired manner.

In operation, the machine knits the body 60 of the article produced as usual, the cam 416 being operative to clear the needles n³ at each course, but upon the end of the lever 110 running off one of the cams 112, occurring substantially at the same time as the 65 beginning of the operation of the splicing

devices, the cam 416 is withdrawn, the plunger 424 entering the path of cams 65^a and 65^b, which reinsert cam 416 at each second revolution, when said cam 416 is opposite the short-butt needles, and retain it 70 in position during passage of all the long butts, to cause the needles n³ to be cleared prior to their next passage of the stitch cams. The cam 416 may be left in its inward position to clear the long butts during 75 knitting of the heel, if desired, be operated during knitting of the body of the foot, and then be withdrawn. This withdrawal may occur just prior to stoppage of the machine, to remove the cam 416 prior to leveling the 80 needles for transfer.

While I have described the placing in the fabric of the tucked mark T with relation to a stocking having a high spliced area and a spliced sole, it will be evident that my devices secure the placing of said mark at any predetermined place in the fabric whether or not said fabric is spliced.

What I claim is:

1. A knitting machine having in combination 90 driving devices including a rotary element, cams on said element and a needle cylinder rotated by said driving devices at a rate greater than that of said element, and tucking means comprising special needles, an advancing cam for said needles, and a mounting for said advancing cam, said mounting and cam being adapted for unitary movement together to move the cam toward and away from said needle cylinder 100 into and out of position to affect said special needles, a part of said mounting near said rotary element being adapted to be actuated by the cams thereon in one position of said mounting.

2. In a circular knitting machine, needles in series having long and short operating butts, special needles at the ends of one of said series, and stitch cams at which said special needles accumulate loops, in combination with a supplemental cam to position the special needles to prepare them for normal knitting at the stitch cams, a lever upon one end of which said cam is mounted, and means acting at recurrent intervals on 115 the other end of said lever during passage of the short butts at said cam to move said cam toward the center of the machine preparatory to acting on the needle butts and thereafter acting to withdraw said cam.

3. A knitting machine having needles, a rotary needle cylinder, and means for driving said cylinder comprising a rotary gear having a cam thereon running at a rate slower than that of said cylinder, in combination with tucking means including a supplemental cam and means for moving said cam toward and away from the needle cylinder to render it operative and inoperative, consisting of a lever carrying said 125 130

cam having its fulcrum between and extending between said cylinder and the cam on said gear.

4. A knitting machine having needles, a rotary needle cylinder, and means for driving said cylinder comprising a rotary gear having a cam thereon running at a rate slower than that of said cylinder, in combination with tucking means including a supplemental cam and means for moving said cam toward and away from the needle cylinder to render it operative and inoperative, consisting of a lever carrying said cam having its fulcrum between and extending between said cylinder and the cam on said gear, and pattern controlled means restraining said lever from operation during predetermined times.
5. In a tucking mechanism for automatic stocking knitting machines, pattern mechanism controlling the knitting devices, stitch cams, needles and a supplemental advancing cam for tucking normally positioned to cause all of the needles to knit, in combination with means controlled by said pattern mechanism to withdraw said cam at the end of a cycle of operations, to permit the needles to be leveled for transfer.
6. In a knitting machine, the combination

of needles, needle and cam carriers, 30 stitch cams, means to rotate one of said carriers, a part moving at a rate related to that of the moving carrier, a supplemental cam for coöperation with some of the needles, and a mounting for said cam comprising a lever having one end movable toward and away from said needle carrier carrying the supplemental cam at said end and having a part in the path of actuating means carried by said moving part, a pattern surface, and means controlled thereby for rendering said lever inoperative by said actuating means.

7. In a knitting machine, the combination of stitch cams, devices for leveling the needles and means to operate said devices at a predetermined revolution, a supplemental cam normally positioned for action, means to withdraw said cam at intervals for tucking, and automatic means acting to 50 withdraw said cam during said revolution.

In testimony whereof, I have signed my name to this specification in the presence of two subscribing witnesses.

ROBERT W. SCOTT.
